United States Patent Office

Des. 189,635
Patented Jan. 24, 1961

189,635

CARD RACK

Homer G. Long, R.R. 5, Franklin, Ind.

Filed July 21, 1960, Ser. No. 61,480

Term of patent 14 years

(Cl. D1—3)

Fig. 1.

Fig. 2.

Fig. 3.

Fig. 4.

Fig. 5.

Fig. 6.

I claim:

The ornamental design for a card rack, as shown.
